US0D1023249S

(12) **United States Design Patent** (10) **Patent No.:** **US D1,023,249 S**
(45) **Date of Patent:** **** Apr. 16, 2024**

(54) **FLUID OUTPUT CONNECTOR**

(71) Applicant: **Botrista Technology, Inc.**, Redwood City, CA (US)

(72) Inventors: **Jia-Hui Chen**, Kaohsiung (TW); **Wu-Chou Kuo**, Taipei (TW)

(73) Assignee: **BOTRISTA TECHNOLOGY, INC.**, Redwood City, CA (US)

(**) Term: **15 Years**

(21) Appl. No.: **29/883,879**

(22) Filed: **Feb. 3, 2023**

Related U.S. Application Data

(62) Division of application No. 29/786,525, filed on Jun. 1, 2021.

(51) **LOC (14) Cl.** **23-01**

(52) **U.S. Cl.**

USPC **D23/262**; D7/307; D7/300

(57) **CLAIM**

The ornamental design for a fluid output connector, as shown and described.

DESCRIPTION

FIG. 1 is a top, front, right side perspective view of a fluid output connector, showing the new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a bottom, rear, left side perspective view thereof. Features shown in broken lines in the drawings form no part of the claimed design.

The flat surface surrounding all the plurality of output ports is not part of the claimed design.

1 Claim, 8 Drawing Sheets
